UNITED STATES PATENT OFFICE.

ELLSWORTH PORTER, OF CLIFTON SPRINGS, NEW YORK.

POTATO-DIGGER.

SPECIFICATION forming part of Letters Patent No. 651,203, dated June 5, 1900.

Application filed January 4, 1900. Serial No. 361. (No model.)

To all whom it may concern:

Be it known that I, ELLSWORTH PORTER, a citizen of the United States, residing at Clifton Springs, in the county of Ontario and 5 State of New York, have invented a new and Improved Potato-Digger, of which the following is a full, clear, and exact description.

One object of the invention is to so construct a potato-digger that the blade adapted 10 to enter the ground may be readily adjusted and likewise the inclination of the elevator, and, furthermore, to provide a receiver adapted to receive the potatoes and earth from the elevator and also means for revolving the receiver, the receptacle being in the nature of 15 a sieve, the body portion consisting of a series of rods supported in cylindrical form and arranged at an angle to the axis of the receiver, so that as the receiver is revolved 20 the earth will be freed from the potatoes and discharged from the receiver and the potatoes will be carried partially up the sides of the receiver and then dropped downward in a central direction, finding their escape at the 25 rear end of the receiver.

Another object of the invention is to provide means for adjusting the cleaning-receiver for the potatoes and to construct a machine of the character above set forth in an 30 exceedingly simple and durable manner.

Another object of the invention is to so construct the machine that it may be made to travel along each row and so that it will not 35 waste any potatoes or cover them up or bruise or damage them in the least, the potatoes being discharged from the machine in narrow rows.

The invention consists in the novel construction and combination of the several 40 parts, as will be hereinafter fully set forth, and pointed out in the claims.

Reference is to be had to the accompanying drawings, forming a part of this specification, in which similar characters of reference indicate 45 corresponding parts in all the figures.

Figure 1 is a side elevation of the improved machine. Fig. 2 is a plan view thereof, parts being in section. Fig. 3 is a vertical section taken practically on the line 3 3 of Fig. 1. 50 Fig. 4 is a transverse section through the cleaning-receiver for the potatoes, the section being taken substantially on the line 4 4

of Fig. 1. Fig. 5 is a rear view of the receiver adapted to clean and discharge the potatoes, and Fig. 6 is a transverse section 55 through the upper portion of the elevator.

The frame of the machine consists of two upper parallel side bars 10, preferably of angle-iron, which are usually inclined slightly downwardly and forwardly, the said side bars 60 being connected at their forward ends by an arch 11, having spindles 12, on which the front supporting-wheels 13 of the machine are mounted, and the thills 14 are attached in any approved manner to the side portions of 65 the said arch. In the further construction of the frame two downwardly-extending angle-bars 10^a are projected from the rear ends of the side bars 10, and horizontal bars 15 are made to extend from the rear portions of the 70 angle side bars 10, as shown in Figs. 1 and 3, the horizontal bars 15 being also preferably angular in cross-section. In order to strengthen the frame, side braces 16 are employed, extending from the vertical members 75 10^a to the side members 10, and brace-plates 16^a are also located where the side and the vertical members of the frame connect, as shown in Fig. 1.

The seat 17 is secured to a platform 18, extending from one side bar 10 of the frame to the other, and preferably a rack 19 is attached to the forward central portion of the platform 18, and a lever 20 is pivoted on the said 80 rack. 85

An elevator A is used in connection with the frame of the machine, being held in a downwardly and forwardly inclined position. The frame of the elevator consists of side bars 21, preferably of angle-iron, and brackets 22, 90 secured to the said side bars, which brackets are also attached to and support side bars 23, extending the full length of the elevator and beyond the conveyer of the elevator, which will be hereinafter described. A digger-blade or shovel 24 is secured to the lower forward portion of the elevator-frame, the said blade or shovel projecting beyond the said frame, and the said shovel is usually brought to a point at the central portion of its cutting 95 edge, as shown in Fig. 2. The forward or lower end of the elevator-frame may be raised and lowered, so that the shovel 24 may be made to enter the ground to a greater or a less 100

- depth, through the medium of uprights 25, attached to the side portions of the elevator-frame and passed loosely through guides 26, secured to the side bars 10 of the main frame 5 of the machine. These uprights are connected by a bail 27, and the bail 27 is connected with the lever 20, above mentioned, by means of a chain 28 or its equivalent. Thus it will be observed that by manipulating the lever 20 10 the shovel may be raised and lowered and likewise that portion of the elevator-frame to which the shovel is attached. The upper portion of the elevator-frame is braced and materially strengthened by applying thereto a 15 cross-bar 29, as shown in Fig. 6. The angled side bars 21 are shown of less length than the side members or plates 23; but the rear end of each angle side bar 21 is attached to an arm 30, and these arms extend downwardly 20 and rearwardly, each forming an angular portion of the sleeve 31, as is shown in both Figs. 2 and 6. These sleeves are mounted loosely in boxes 32, and, as shown in Figs. 1 and 2, the boxes are mounted to slide upon the lower 25 portions of the angle members 10^a of the main frame, the boxes being provided with bolts or pins 33, which extend outwardly through slots 34, made in the rear of the said vertical members 10^a, as shown in Fig. 3.
- 30 A shaft 35 is journaled in the sleeves 31, as shown in Fig. 6, and within the sides of the frame of the elevator two large sprocket-wheels 35^a are secured to the shaft 35, and chain belts 36 are passed over these wheels 35^a and over smaller sprocket-wheels 37, located on a shaft 37^a, journaled in suitable bearings near the lower end of the elevator-frame, as shown in Fig. 1. The chain belts 36 constitute portions of the conveyer for the 35 elevator-frame, and the construction of the conveyer is completed by securing boards or bars 38 transversely to the said chain belts, usually quite close together, and locating transverse partitions 39 on the outer faces of 40 sundry of the said bars or boards, as shown in Fig. 1, the partitions serving to carry up the potatoes and earth that may cling thereto to the cleaner and distributer, to be herein-after described.
- 45 Runners 40 are located at the bottom portion of the elevator near the blade or shovel 24, and slats 41 or their equivalents are carried from runner to runner, so as to prevent the earth from being brought in direct engagement with the lower foot portion of the conveyer. Hangers 42 are journaled upon the sleeves 31 near their outer ends, as shown in Fig. 2, and each of said hangers is provided with a rearwardly-extending tubular 50 section 43 at right angles to the main section or body of the hanger, and each hanger 42 is also provided with a forwardly-extending arm 44, the arms being inclined upward, as illustrated in Figs. 1 and 2. A shaft 45 is journaled in the tubular sections of the hangers 42, and the rear supporting-wheels 46 are loosely mounted on the ends of the shaft. 55

Each tubular section 43 of each hanger 42 is provided at its outer end with a clutch or ratchet face engaged by spring-controlled pawls 48, located in suitable boxes formed in the hubs of the rear wheels. This connection is made in order that when the machine turns a corner or is turned around one wheel will advance, while the other wheel will remain 75 practically stationary or will move slightly backward, serving as a pivot.

When the shovel end of the elevator is raised or lowered, it is desirable to change the inclination of the body of the elevator, and 80 this is accomplished by attaching links 49 or their equivalents to the forwardly-extending arms 44 of the hangers 42, which links are attached to said arms by means of pins 50, as shown in Fig. 3, and the links are likewise 85 attached to pins 51, formed upon crank-arms 52, carried by a shaft 53, which shaft is journaled at the main portion of the frame and usually passes through a rack 54, the shaft being provided with a lever 55, whereby it 90 may be turned, and this lever carries a thumb-latch arranged for engagement with the rack 54.

The driving-shaft 35 of the conveyer is provided at one end with a bevel-gear 57 and 95 with a pinion 58, which forms a portion of the bevel-gear or is attached thereto, as shown in Fig. 6. The bevel-gear 57 is adapted to communicate motion to the receiver or receptacle B for the potatoes in a manner which 100 will be hereinafter described, and the shaft 35 receives motion from the shaft 45 by placing a large gear 59 on one end of the shaft 45, which meshes with the pinion 58 on the driving-shaft of the conveyer.

The receiver B for the potatoes is located at the rear of the machine and is capable of being given any inclination. This receiver consists of a tubular head 60, having an outwardly-extending annular flange 61 at its upper end, and at the lower edge of the said head 60 an exterior gear 62 is secured or formed. A ring 63 is located a desired distance below the head 60, and rods 64 are attached to the head 60 and are passed through 110 apertures in the ring 63. The rods are not carried straight through the head of the ring, but spirally or diagonally, as is shown in Figs. 1 and 2.

The receiver B is supported by a frame C. 120 This frame preferably consists of two side bars 65, having angle-sections 66 at their upper ends, which angle-sections are pivoted upon the sleeves 31, journaling the driving-shaft 35 of the conveyer, as shown best in Fig. 125 2. These arms 65 are attached to a ring 67, located at the exterior of the head 60, between its flange 61 and the gear 62, and the side bars 65 of the frame are also attached at their lower ends to a second ring 68, which is located over and is concentric with the lower ring 63 of the receiver. The side bars are attached to the two outer rings 67 and 68 by means of bolts 66^a or their equivalents, and 130

the head-ring 67 is likewise secured to the side arms 65 by braces 65^a. The head-ring 67 is provided with a series of laterally-arranged friction-wheels 69, adapted to engage with the flange 61 of the head of the receiver, and also with a series of vertically-arranged friction-wheels 70, adapted to engage with the outer surface of the head, and the outer or frame ring 68 is provided with a series of friction-rollers 71^a, which are adapted to travel upon the outer surface of the structural ring 63 of the receiver. Thus it will be observed that roller-bearings are provided for the receiver B. The receiver is raised and lowered by attaching a bail 72 to the lower guide-ring 68 and attaching a chain 73 to the said bail, which chain is carried upward over a roller 74, located in the extension 15 of the frame, and the upper end of the chain is attached to a lever 75, fulcrumed upon the said extension and having a thumb-latch arranged for engagement with a suitable rack 76.

A box 77 is located at the inner end portion of one of the side bars 65 of the supporting-frame for the receiver, and another box 78 is located upon the head-ring 67 of the said supporting-frame, as shown in Figs. 1 and 2. A shaft 79 is mounted to turn in these two boxes, and the shaft is provided at one of its ends 30 with a bevel-gear 80, which meshes with the bevel-gear 57 on the driving-shaft for the conveyer, and a plain gear 81 is secured to the other end of the shaft, arranged to mesh with the gear 62, located on the head of the receiver 35 B. Under this arrangement as the machine advances the receiver B is constantly revolved.

The potatoes as they are dug are taken up on the conveyer and are deposited in the receiver B. As the said receiver revolves the potatoes will be carried up the sides of the receiver, owing to the arrangement of the bars 64, until their tendency is to move downward, whereupon they will fall toward the center 45 and lower end of the receiver and by so doing will slide lengthwise upon the rods 64, which will sift the earth from the potatoes, and the potatoes, practically clean and without bruises, will be dropped out at the lower 50 end of the receiver, forming a narrow row on the ground, from whence they may be readily removed.

Having thus described my invention, I claim as new and desire to secure by Letters 55 Patent—

1. In a potato-digger, the combination with a frame, of an elevator having its rear end hinged in the frame, means for raising and lowering the front end of the elevator, pivoted hangers carried by the frame, supporting-wheels having their axle mounted in the hangers, and means for swinging the hangers on their pivots, substantially as described.

2. In a potato-digger, the combination with a frame, of an elevator having at its rear end bearings mounted in adjustable boxes carried by the frame, hangers pivotally mount-

ed on said bearings, supporting-wheels having their axle mounted in the hangers, and means for swinging the hangers, substantially as described. 70

3. In a potato-digger, the combination with a frame, of an elevator-frame having sleeves at its rear end, said sleeves being mounted in boxes carried by the frame, a shaft mounted in the sleeves and carrying sprocket-wheels, a shaft at the front end of the elevator-frame and carrying sprocket-wheels, an endless elevator-belt passing around said sprocket-wheels, hangers loosely mounted on the sleeves, supporting-wheels having their axle mounted in the hangers, and means for operating the hangers, substantially as described. 75

4. In a potato-digger, the combination with a frame, of an elevator-frame having sleeves at its rear end, boxes adjustably secured to the frame and in which the said sleeves are mounted, a shaft mounted in the sleeves and carrying sprocket-wheels, a shaft at the front 90 end of the elevator-frame and carrying sprocket-wheels, an endless elevator-belt passing around said sprocket-wheels, hangers loosely mounted on the sleeves, supporting-wheels having their axle mounted in the 95 hangers, means for swinging the hangers on the sleeves, and means for raising and lowering the front end of the elevator-frame, substantially as described. 100

5. In a potato-digger the combination with a frame, an elevator having its rear end hinged to the frame, pivoted hangers carried by the frame, supporting-wheels having their axle mounted in the hangers, and means for swinging the hangers on their pivots, of 105 bars having their lower ends pivoted to the front of the elevator and their upper ends working in guides carried by the frame, a bail secured to said bars, an operating-lever carried by the frame, and a flexible connection between the lever and bail, substantially as described. 110

6. In a potato-digger the combination with a frame, of hangers pivoted to the frame and each having a rearwardly-extending 115 tubular section provided with a clutch or ratchet face, a shaft mounted in the said sections, wheels mounted on the shaft, and spring-pawls mounted in the hubs and engaging the clutch or ratchet faces of the said 120 sections, substantially as described.

7. In a potato-digger, the combination with a wheel-supported frame, and an elevator carried thereby, of a pivoted and adjustable frame, comprising side bars and rings, one of 125 which is provided with two sets of friction-wheels arranged at right angles to each other, a cylindrical receiver mounted in the frame and having a flanged end with which flange one set of the friction-wheels of the said ring 130 engages, the other set of friction-wheels engaging the head of the receiver, and means for revolving said receiver, substantially as described.

8. In a potato-digger, the combination with a wheel-supported frame, and an elevator carried thereby, of a pivoted and adjustable frame, comprising side bars and rings between the side bars, the head-ring being provided with two sets of friction-wheels arranged at right angles to each other, and the other ring with a single set of friction-wheels, a cylindrical receiver mounted in the frame and having a flanged front end and an exterior gear, between which flange and gear the head-ring is arranged, a shaft driven from the axle of the drive-wheel and provided with a gear meshing with the gear of the receiver, substantially as described.

9. In a potato-digger, the combination with a wheel-supported frame, an elevator-frame having sleeves at its ends said sleeves being mounted in boxes carried by the frame, an elevator-belt carried by the said frame, a shaft mounted in the sleeves and provided with two gear-wheels at one end, and means for operating the shaft from the axle of the supporting-wheels, of a rearwardly-extending frame mounted on the sleeves of the elevator-frame, means for adjustably supporting the rear end of the frame, a cylindrical receiver mounted to revolve in the frame and

provided with an exterior gear-wheel, and a shaft provided with a gear-wheel at each end, one of the gear-wheels meshing with the gear of the receiver and the other with the gear of the shaft mounted in the sleeves of the elevator-frame, substantially as described.

10. A potato-digger, comprising a frame, supporting-wheels having their axle mounted in adjustable hangers on said frame, an elevator-frame having its rear end pivoted to the frame and provided with a shovel at its front end, an endless elevator-belt mounted in the frame and operated from the axle of the supporting-wheels, means for raising and lowering the front end of the elevator-frame, a cylindrical receiver pivotally and rotatably mounted at the rear of the frame, and gearing between the elevator-belt-operating mechanism and the receiver, substantially as described.

In testimony whereof I have signed my name to this specification in the presence of two subscribing witnesses.

ELLSWORTH PORTER.
